Primary Examiner — Jennifer Rivard(74) *Attorney, Agent, or Firm* — Andrew W. Chu; Craft Chu PLLC(57) **CLAIM**

The ornamental design for the manicure drill bit, as shown and described.

DESCRIPTION

FIG. 1 is an upper perspective view of the manicure drill bit showing my design.

FIG. 2 is a front elevation view thereof, a back elevation, side elevation, and opposite side elevation being identical; FIG. 3 is a top plan view thereof; and, FIG. 4 is a bottom plan view thereof.

The manicure drill bit is a rotary nail drill bit for use in manicure and pedicure treatments.
